US00D455437S

(12) **United States Design Patent** (10) Patent No.: **US D455,437 S**
(45) Date of Patent: ** Apr. 9, 2002

(54) **TROLLING MOTOR FOOT PAD PEDAL**

(75) Inventors: **Steven J. Knight**, Madison Lake; **Ronald P. Hansen**, Mapleton, both of MN (US); **Jeffrey Kalman**, Cleveland Heights; **Craig M. Saunders**, Rocky River, both of OH (US)

(73) Assignee: **Johnson Outdoors Inc.**, Sturtevant, WI (US)

(**) Term: **14 Years**

(21) Appl. No.: **29/124,860**

(22) Filed: **Jun. 13, 2000**

(51) LOC (7) Cl. **15-01**

(52) U.S. Cl. **D15/4**

(58) Field of Search D15/4; D12/125; 84/426, 721, 746; 440/6, 7, 56, 63

(57) **CLAIM**

The ornamental design for a trolling motor foot pad pedal, as shown and described.

DESCRIPTION

FIG. 1 is a perspective view of the trolling motor foot pad pedal of the present invention;

FIG. 2 is a left end elevational view thereof;

FIG. 3 is a right end elevational view thereof;

FIG. 4 is a front elevational view thereof;

FIG. 5 is a rear elevational view thereof; and,

FIG. 6 is a bottom plan view thereof.

The broken lines in the drawings are for illustrative purposes only and form no part of the claimed design.
